UNITED STATES PATENT OFFICE.

JOHANN L. BRAUN, OF PITTSBURG, PENNSYLVANIA.

BRICK.

SPECIFICATION forming part of Letters Patent No. 729,918, dated June 2, 1903.

Application filed November 26, 1902. Serial No. 132,885. (No model.)

To all whom it may concern:

Be it known that I, JOHANN L. BRAUN, a citizen of the United States of America, residing at Pittsburg, in the county of Allegheny, and 5 State of Pennsylvania, have invented certain new and useful Improvements in Bricks, of which the following is a specification, reference being had therein to the accompanying drawings.

10 This invention relates to certain new and useful improvements in building-brick, and relates more particularly to that class of brick employed for building furnaces and like walls, the invention having for its object to construct a brick with longitudinal and vertical openings whereby when the wall is complete 15 a series of continuous horizontal flues and also a series of continuous vertical flues will be provided throughout the wall in order to 20 permit the circulation of cool air to preserve the wall.

Briefly described, my improved building-brick comprises two sections or members 25 adapted to match together, each section being provided on its matching face with a semicircular groove extending throughout the length of the brick whereby when the sections are 30 matched together the cylindrical flue or opening will be provided centrally throughout 35 the length of the brick. The sections are provided on their matching faces with tongues and grooves whereby the sections will match neatly together. Each section is also provided with one or more vertical openings 40 whereby the vertical flues will be formed in 45 the furnace-wall, as well as the horizontal flues, when the wall is complete. In the corner-brick for the walls I preferably construct the one leg of the same approximately twice 50 the length of the other leg, the longer leg being provided with two vertical openings and the shorter leg with a single vertical opening.

In describing the invention in detail reference is had to the accompanying drawings, 55 forming a part of this specification, and wherein like numerals of reference indicate like parts throughout the several views, in which—

Figure 1 is a detail perspective view of the 60 upper section or member of the brick. Fig. 2 is a like view of the lower section or member. Fig. 3 is an end view of the sections

matched together. Fig. 4 is a top plan view of the lower section. Fig. 5 is a plan view of the corner-brick. Fig. 6 is a detail perspective view of a modified form of brick. Fig. 7 is a horizontal sectional view of the same, showing in dotted lines how the bricks of this form are matched together. Fig. 8 is a top plan view, and Fig. 9 is an end view, 60 thereof.

In accordance with my invention I construct the brick by molding the same in two sections, the upper section 1 being provided throughout its matching face with a semicircular groove 2 and adjacent the edge of this groove with a tongue 3, this tongue being formed by shouldering off the face of the brick, as at 4. The lower section or member 5 of the brick is also provided with a semi-cylindrical groove 6 and with ledges 7, which are adapted to fit on the shouldered-off faces 4 of the section 1, the section 5 having shouldered faces 8, which are adapted to receive the tongues 3 of the section 1. Each of the sections 75 is provided with vertical apertures 9, which apertures in the sections aline when the sections are matched together, whereby a series of continuous vertical flues are provided throughout the wall, and when the sections 80 are matched together the semicylindrical grooves 2 and 6 form the continuous horizontal flue 10, extending throughout each course of the bricks.

In the construction of the corner-brick in 85 accordance with my invention I mold the same in two sections, comprising the legs 11 and 12, as shown in Fig. 5, extending at substantially right angles to each other and the former being preferably constructed about twice the 90 length of the latter. The sections of the corner-brick are matched together in the same manner as the straight-line bricks and are provided with the horizontal flue 10 and a series of vertical flues 9, the longer leg being provided with two of these flues and the shorter leg with a single flue. The brick is made of any suitable refractory material, such as generally employed for the construction of furnace-bricks.

In Figs. 6 to 9 I show a modified form of construction in which the brick is cut away on opposite faces at its ends, forming the half-sections 11' 12', which are integral with

the body portion 14. The section or extension 11' of the one brick receives thereon the extension 12' of the adjacent brick. The section or extension 12' are provided with longitudinal shoulders 15, which are formed by shouldering off the face of the extension, as at 16, these shoulders 15 fitting in the shouldered-off portions 17 of the extensions 11' of the adjacent brick. The extensions 11' and 12' are provided with semicircular grooves, so that when the bricks are matched together the continuous horizontal flue is provided throughout the series of bricks and the extensions are provided with vertical flues or openings 18, which register when the bricks are matched together, and the central or body portion of the brick is also provided with a vertical flue 19. The manner in which these bricks are matched together is clearly shown in Fig. 7 of the drawings.

Having fully described my invention, what I claim as new, and desire to secure by Letters Patent, is—

1. A furnace-brick comprising matching sections, tongues on one of the sections adapted to match with the other section, each section provided with a longitudinal semicircu-

lar groove in its matching face, and vertical flues formed in each of the sections and extending through the brick, substantially as described.

2. A furnace-brick comprising an upper and a lower section adapted to match together, the upper sections having tongues adapted to match with the shouldered-off portions in the lower section, and the lower section having ledges adapted to match with the shouldered-off portions of the upper section, each of said sections having a semicylindrical groove in its matching face and provided with vertical openings, as and for the purpose described.

3. A furnace-brick comprising matching sections, one section having tongues adapted to match with the other section, and each section having vertical and longitudinal flues extending therethrough, substantially as described.

In testimony whereof I affix my signature in the presence of two witnesses.

JOHANN L. BRAUN.
